US00D463043S

(12) **United States Design Patent** (10) Patent No.: **US D463,043 S**
Edger (45) Date of Patent: ** Sep. 17, 2002

(54) **SASH REINFORCEMENT FRAME**

Primary Examiner—Doris Clark

(75) Inventor: **Ronald Frederick Edger**, Bolton (CA)

(57) **CLAIM**

(73) Assignee: **Royal Group Technologies Limited**,
Woodbridge (CA)

An ornamental design for a sash reinforcement frame, as
shown and described.

(**) Term: **14 Years**

(21) Appl. No.: **29/141,025**

DESCRIPTION

(22) Filed: **Apr. 30, 2001**

FIG. 1 is a perspective of the sash reinforcement frame
showing my new design; and,

(51) LOC (7) Cl. **25-01**

FIG. 2 is an end elevational view of the sash reinforcement
frame of FIG. 1.

(52) U.S. Cl. **D25/119**

The sash reinforcement frame is broken in the center indicating
indeterminate length.
